UNITED STATES PATENT OFFICE.

MORRIS LEIBERMAN, OF CHICAGO, ILLINOIS.

COLLAPSIBLE BOX.

Application filed March 6, 1926. Serial No. 92,845.

This invention relates to certain novel improvements in collapsible boxes and has for its principal object the provision of an improved construction of this character which 5 will be highly efficient in use and economical in manufacture.

Among the salient objects of the invention is the production of a box of this character wherein there is provided a simple combination of parts for locking the wall portions of the box in distended position and wherein by the removal of the locking elements the walls of the box can be expeditiously collapsed to provide a small compact condition 10 of the box when in collapsed position to facilitate returning of the box from the consignee to the original shipper.

In accordance with one object of the invention there is provided an element, hereinafter referred to as the main locking element, which serves as an instrument for locking certain of the wall portions of the box when in distended position and wherein this element in turn is employed to lock certain 20 other elements which are employed to lock certain of the wall portions in distended position.

Other objects will appear hereinafter.

The invention consists in the combination 30 and arrangement of parts hereinafter described and claimed.

The invention will be best understood by reference to the accompanying drawings illustrating the preferred form of construction, and in which

Fig. 1 is a perspective view of the box embodying the invention illustrating certain wall portions thereof in open position,

Fig. 2 is a perspective view of the box illustrated in Fig. 1 showing the box in collapsed position,

Fig. 3 is a top plan view of the box illustrated in Fig. 1 showing a part of the cover thereof removed,

Fig. 4 is a fragmentary sectional detail view taken substantially on line 4-4 of Fig. 3,

Fig. 5 is a fragmentary sectional detailed view taken substantially on line 5-5 of Fig. 3,

Referring more particularly to the drawings, especially to Fig. 1, the bottom wall of the box is indicated at 10. To this bottom wall are permanently hinged, through the 55 medium of exterior hinge members 11, side walls 12 and 13. To the side wall 12 oppo-

site the hinge connection 11 is permanently hinged through the medium of an exterior hinge member 14 a top wall or cover 15. To the bottom wall 10 is also permanently hinged, through a medium of exterior hinge members 16, end walls 17. The end walls 17 are detachably secured to the side walls 12 and 13 through the medium of interfitting lug members 18 and 19. These lug members 18 and 19 include lug wings 20 defining knuckles 21 arranged in aligned relation and adapted to receive removable pintles or lock pins 22 and 23 having head portions 24 serving to limit insertion of these lock pins 70 through the knuckles 21. The cover 15 is detachably secured to the end walls 17 through the medium of interior lug members 25. These lug members 25 include leaf members 26 defining knuckles 27 arranged in aligned 75 relation adapted to receive removable pintles 28. The side wall 13 has formed therein openings 29 which are adapted for alignment with the openings 30 formed in the knuckles 26' of the lug wings 26 when this 80 side wall is disposed in distended position with respect to the end walls 17. These openings 29 permit the insertion of the pintles 28 through the openings 30 of the knuckles 26 when the cover 15 is disposed in distended relation with respect to the end walls. In Fig. 5 it will be noted that corresponding ends 31 of the pintles 28 are adapted for abutment with the inner wall surfaces of the side wall 12 and that opposite corresponding end portions 31' are disposed inwardly of the heads of the pintles 28 for reasons hereinafter understood. The corresponding end portions 31, as illustrated in Fig. 5, are normally disposed in the path of withdrawal of the pintles 22 and in this position these end portions serve to prevent upward movement of the pintles 22.

The cover 15 is likewise detachably connected to the side wall 13 through the medium of a lug member 32 including lug wings 33 having aligned knuckles 34 bored to receive the main locking pin 35. To permit insertion of the main locking pin 35 through the knuckles of the lug-wings 33 there is formed in corresponding corners of the end walls 17 aligned openings 35' through which this main locking pin is inserted when portions thereof are confined in the bores of the knuckles 34. As will be 100 noted in Fig. 4 the main locking pin 35 is disposed in the path of withdrawal of the

locking pins 23 so as to prevent upward movement of these locking pins. It will be likewise noted in Fig. 5 that this locking pin is disposed in the path of withdrawal of the locking pins 28 through the openings 29 thereby preventing self-displacement of these locking pins.

Provision is made for preventing self-displacement of the main locking pin 35. In the present instance this main locking pin includes an end portion 36 bifurcated as at 37 to receive a latch plate 38 which is pivotally carried by this main pin, at its bifurcated end portion through the medium of a suitable pivot pin 39. It is intended that this latch plate, when the main lock pin 35 is inserted in the position illustrated in Fig. 4, will by reason of gravity dispose itself in a position substantially at right angles with respect to the bifurcated end portion of this main locking pin so that in disposing itself in this position withdrawal of the main locking pin is resisted.

The end portion of the main locking pin 35, opposite the bifurcated end portion thereof, defines a handle portion 40 to facilitate withdrawing of the main locking pin from the position illustrated in Fig. 4, when the latch plate is disposed in aligned position with this pin.

In order to prevent unauthorized removal of this locking pin there is provided in the main locking pin at the bifurcated end portion thereof, inwardly of the pivot pin 39 aligned openings 41 for the reception of a wire shank 42 of a seal 43 of any approved type. If this seal is found broken it will indicate that the main locking pin has been withdrawn by one not authorized to do so.

In collapsing the box thus far described, the main locking pin and the locking pins 22, 23 and 28 are withdrawn from the knuckles of the lug wings to permit the end walls 17 to be folded upon the bottom wall 10 and to permit the side wall 12 and cover 13 to be folded upon the bottom 10 opposite the end walls 17 and upon the side wall 13 respectively. In this collapsed condition of the box it is apparent that a small compact parcel is provided greatly facilitating returning of the box in the collapsed condition to the shipper.

The folding of the end wall 17 upon the under side of the bottom 10 is permitted by reason that in the preferred form of construction the hinge members 16 are disposed with the hinge leaves 16' thereof on the exterior surfaces of these end walls and bottom wall 10.

The meeting edges of the wall portions making up the box when in distended position are bevelled as at 44 to permit a tight line of junction between the meeting edges of the walls herein mentioned.

By reference to the accompanying draw-

ings it will be noted that there is provided on the wall surfaces of the wall portions making up the box opposite each of the hinge leaves a reinforcing strip 45 which is arranged to receive the connecting elements 70 47 which serve to secure the leaf members of the hinges to their respective wall portions of the box.

From the description herein it will be manifest that I provide a simple combination and arrangement of parts for effectively locking the wall portions making up the box in distended position and that this simple combination and arrangement of parts permits expeditious collapsing of these wall portions.

While I have illustrated the preferred form of construction of my invention, it is to be understood that various changes and alterations may be carried out in manufacture without departing from the spirit of the invention or the scope of the appended claims.

The device having been set forth, what I claim as new and useful is:

1. A box of the class described including a body defining a bottom wall and side and end walls permanently hinged to the bottom wall, means detachably connecting the side and end walls in distended position, said means including lug members having removable pintles, a cover permanently hinged to one of the side walls, means detachably connecting the cover to the other of the side walls and to the end walls, said last mentioned means including lug members having removable pintles, certain of the pintles of said last mentioned lug members having end portions disposed in the path of withdrawal of certain of the pintles of the first mentioned lug members.

2. A box of the class described including a body defining a bottom wall and side and end walls permanently hinged to the bottom wall, means detachably connecting the side and end walls in distended position, said means including lug members having removable pintles, a cover, means detachably connecting the cover to one of the side walls, said last mentioned means including lug members having removable pintles, certain of the pintles of said last mentioned lug members having portions disposed in the path of withdrawal of certain of the pintles of said first mentioned lug members.

3. A box of the class described including a body defining a bottom wall and side and end walls, means detachably connecting the side and end walls in distended position, a cover, means permanently hingedly connecting the cover to one of the side walls, means detachably connecting the cover to the other of the side walls, said means including a connecting pin, a gravity actuated latch member carried at one end portion of

the connecting pin and adapted for engagement with one of the end walls to prevent withdrawal of the connecting pin, and a handle portion formed on the opposite end 5 of the connecting pin.

4. A box of the class described including a body defining a bottom wall and side and end walls, means connecting the side and end walls to the bottom wall, means including 10 lug members having removable pintles providing connection between the end walls and the side walls, a cover, means including a lug member having a removable attaching pinte providing detachable connection between the cover and one of the side walls, said pinte having end portions disposed in the path of withdrawal of certain of the 15 said pintles, means providing hinge connection between the cover and the other of the side walls, and means including lug members having removable pintles providing detachable connection between the cover and the end walls, said last mentioned pintles being in turn obstructed from removal by aforementioned connecting pin.

5. A box of the class described including a body defining a bottom wall and side and end walls, means hingedly connecting the side and end walls to the bottom wall, a cover 20 having a hinge connecting with one of the side walls, means connecting the end walls to the side walls, said last-mentioned means including lug members having removable pintles, means connecting the cover to the end walls, said last-mentioned means including lug members having removable pintles with corresponding end portions of the pintles adapted to be disposed in the path of withdrawal of certain of the first 25 mentioned pintles, means connecting the cover to the other of the side walls, said last-mentioned means including lug member, a removable connecting pin having an end portion defining a handle, and gravity actuated latch plate pivotally carried at the opposite end of the connecting pin, said handle portion and latch plate co-operating together to prevent self-displacement of the connecting pin, said connecting pin being adapted to be 30 disposed in the path of withdrawal of the other of the said first mentioned pintles and in the path of withdrawal of said second mentioned pintles, and reinforcing strips extending along the peripheral edges of the 35 walls.

6. A box of the class described including a body defining a bottom wall and side and end walls, means hingedly connecting the side and end walls to the bottom wall, a cover having a hinge connecting with one of the side walls, means connecting the end walls to the side walls, said last-mentioned means including lug members having removable pintles, means connecting the cover to the end walls, said last-mentioned means including lug members having removable pintles with corresponding end portions of the pintles adapted to be disposed in the path of withdrawal of certain of the first 50

65

mentioned pintles, means connecting the cover to the other of the side walls, said last-mentioned means including lug member, a removable connecting pin adaptable to be disposed in the path of withdrawal of 70 the first mentioned pintles having an end portion defining a handle, a gravity actuated latch plate pivotally carried at the opposite end of the connecting pin, said handle portion and latch plate cooperating together to prevent self-displacement of the connecting pin, said connecting pin being adapted to be disposed in the path of withdrawal of the other of said first mentioned pintles and in the path of withdrawal of 75 said second mentioned pintles.

7. A box of the class described including a body defining a bottom wall and side and end walls, means hingedly connecting the side and end walls to the bottom wall, a cover 80 having a hinge connecting with one of the side walls, means connecting the end walls to the side walls, said last-mentioned means including lug members having removable pintles, means connecting the cover to the end walls, said last-mentioned means including lug members having removable pintles with corresponding end portions of the pintles adapted to be disposed in the path of withdrawal of certain of the first 85 mentioned pintles, means connecting the cover to the other of the side walls, said last-mentioned means including lug member, a removable connecting pin having an end portion defining a handle, and gravity actuated latch plate pivotally carried at the opposite end of the connecting pin, said handle portion and latch plate co-operating together to prevent self-displacement of the connecting pin, said connecting pin being adapted to be 90 disposed in the path of withdrawal of the other of the said first mentioned pintles and in the path of withdrawal of said second mentioned pintles, and reinforcing strips extending along the peripheral edges of the 95 walls.

8. A box of the class described including a body defining a bottom wall and side and end walls, having bevelled meeting edges, means hingedly connecting the side and end walls to the bottom wall, a cover having a hinge connecting with one of the side walls, means connecting the end walls to the side walls, said last-mentioned means including lug members having removable pintles, 100 means connecting the cover to the end walls, said last-mentioned means including lug members having removable pintles with corresponding end portions of the pintles adapted to be disposed in the path of withdrawal of certain of the first mentioned pintles, means connecting the cover to the other of the side walls, said last-mentioned means including lug members, a removable connecting pin having an end portion defining 105 110 115 120 125 130

a handle portion, and a gravity actuated latch plate pivotally carried at the opposite end of the connecting pin, said handle portion and latch plate cooperating together to prevent self-displacement of the connecting pin.

9. The combination with a lug member including lug wings defining aligned interlocking knuckles, of a connecting pin passing through the knuckles for connecting the lug wings together, said connecting pin having an end portion defining a handle and an opposite end portion bifurcated, and a latch bolt pivotally carried by the connecting pin at the bifurcated end thereof adapted to be disposed substantially at right angles with respect to the connecting pin to cooperate with the handle portion to pre-

vent self-displacement of the connecting pin.

20

10. The combination with a lug member including lug wings defining aligned interlocking knuckles, of a connecting pin passing through the knuckles for connecting the lug wings together, said connecting pin having an end portion defining a handle and an opposite end portion bifurcated, and a gravity actuated latch bolt pivotally carried by the connecting pin at the bifurcated end thereof adapted to be disposed substantially at right angles with respect to the connecting pin to cooperate with the handle portion to prevent self-displacement of the connecting pin.

25

30

In testimony whereof I affix my signature.
MORRIS LEIBERMAN.
